US0D1025839S

(12) **United States Design Patent** (10) Patent No.: **US D1,025,839 S**
(45) Date of Patent: ** May 7, 2024

(54) **MOTOR SCOOTER**

(71) Applicant: **PIAGGIO & C. S.P.A.**, Pontedera (IT)

(72) Inventors: **Marco Lambri**, Pontedera (IT); **Marco Canepa**, Pontedera (IT)

(73) Assignee: **PIAGGIO & C. S.P.A.**, Pontedera (IT)

(**) Term: **15 Years**

(21) Appl. No.: **35/516,991**

(22) Filed: **Apr. 5, 2023**

(80) **Hague Agreement Data**

Int. Filing Date: **Apr. 5, 2023**

Int. Reg. No.: **DM/228273**

Int. Reg. Date: **Apr. 5, 2023**

Int. Reg. Pub. Date: **Apr. 28, 2023**

(30) **Foreign Application Priority Data**

Nov. 8, 2022 (EM) 015002610

(51) **LOC (14) Cl.** **12-11**

(52) **U.S. Cl.**

USPC **D12/110**
